Peter Lawson Lowell, Illus.

Letters Patent No. 212 dated April 10th - 1849

(The schedule referred to in these Letters Patent and
making part of the same)

To all to whom these presents shall come. Be it known
that I Peter Lawson of Lowell in the County of Middlesex
and State of Massachusetts have invented or discovered
a new pattern to be woven or printed on carpeting &c &c
and that the following is a full, clear, and exact description
of the principle or character which distinguishes it from
all other things before known, reference being had to the
accompanying drawing numbered 751. -

This design consists of a white shield (a) over which
there is put a yellow leaf (b) and flower stalks which
terminate in a red flower (c) and in addition thereto
there is a spike of brown flowers, or small leaves on
a vine stalk; the sides of the frame of the shield are
bordered ruby and brown, and outside of them there is
a monopetalous flower (d) shaped somewhat like a
horn of plenty, from which issues stamens on one side
pink with white, on the other with blue. The top of the
shield is crowned with a triple banded scroll (e) turned
outward on each side in leaves, and a large leaf

2

Dec. 212

ff, above, outside the shield frame, on a white ground, are yellow and brown leaves, intermingled with green and red, and blue flowers, brown sprigs & a covering of large portion of the ground work.

Having thus fully described my design for Carpets and other similar fabrics I desire to secure the same by letter patent, a full illustration being given in the drawing accompanying.
